UTILITY RACK

Edward W. Hanson, Stillwater, Minn.

Application May 27, 1955, Serial No. 36,258

Term of patent 14 years

Fig. 1 (Cl. D33—3)

Fig. 2

Fig. 1 is a perspective view of a utility rack showing my new design, said view being taken from a position above and to one side thereof;

Fig. 2 is a side elevation view of the same; and
Fig. 3 is a top plan view of the same.

I claim:

The ornamental design for a utility rack, as shown.
